UNITED STATES PATENT OFFICE.

THEODORE M. CLARK, OF NEWTON, MASSACHUSETTS.

APPARATUS FOR FORMING CURVED SURFACES.

SPECIFICATION forming part of Letters Patent No. 547,138, dated October 1, 1895.

Application filed July 5, 1894. Serial No. 516,624. (No model.)

To all whom it may concern:

Be it known that I, THEODORE M. CLARK, of Newton, in the county of Middlesex and State of Massachusetts, have invented certain new and useful Improvements in Apparatus for Forming Curved Surfaces, of which the following is a specification.

The prime object of the present invention is to provide an apparatus whereby a true parabolic surface can be produced on lenses for use in cameras. It is well known that a paraboloidal lens possesses great advantages over a spherical lens by reason of its annulling spherical aberration. The difficulty heretofore attending the production of paraboloidal lenses and the consequent expense has made their employment very limited.

I have devised an apparatus of comparatively simple construction which will accurately form paraboloidal surfaces in a thoroughly practical manner.

My invention is based upon the known principle that if one leg of a right angle passes through the focus of a parabola while the vertex of the angle moves in a line tangent to the parabola at its apex the other leg of the right angle will always be tangent to the parabola.

In addition to the capability of the apparatus to produce paraboloidal surfaces it may be adapted for the production of surfaces of other contour.

An embodiment of the invention is illustrated in the accompanying drawings, which form part of this specification.

Figure 1 shows a perspective view of a machine embodying the invention. Fig. 2 shows a section on line 2 2 of Fig. 1. Fig. 3 shows a section on line 3 3 of Fig. 1. Fig. 4 shows a top plan view of the machine.

The supporting-frame of the apparatus comprises a base *a*, adapted to stand on a bench or other elevated support, a pair of uprights *a'* at opposite sides of said base, and another pair of uprights *a''* at the other two opposite sides of the base. The uprights *a'* are slotted vertically, and guide-strips *b* are secured at opposite sides of the slots, said strips being set obliquely for convenience in assembling the parts. A block *c* is fitted to each set of guiding-strips, and one of said strips is marked with graduations and the adjacent edge of the

block carries a vernier. The block is tapped to receive a vertical adjustment-screw *d*, whose opposite ends are journaled in bearings *d'*, 55 fastened across the ends of the slideways formed by the strips *b*. A milled head *d''* on said screw provides means for turning the latter, and an extremely accurate and minute adjustment can be secured by the reading of 60 the vernier.

Each of the blocks *c* carries on its inner side a disk *c'*, having trunnions which journal in the block and in a bracket *c''*, fastened to the block, and the said disk is slotted diametrically to receive the pendent arm *e* of a frame *e'*, which lies in a plane at right angles to the arms *e* and carries an abrading-disk *f* in the same plane.

Horizontal guideways *g* are arranged on the inner sides of the uprights *a'* at right angles to the vertical ways *b*, and pins *e''*, projecting from the ends of the frame *e'*, enter said guideways.

The uprights *a''* support a horizontal bar *a''*, 75 in which a vertical spindle *h* finds a bearing, and the upper end of said spindle carries a chuck *h'*, in which is removably secured a suitable support *h''* for the lens 2, the latter being cemented to the support. The spindle 80 extends down through the base *a* and the bench and through a bracket *i'*, fastened under the bench, and a pulley *j* is affixed to the spindle to receive rotary motion from any suitable source. The spindle is arranged to slide 85 vertically to accommodate different thicknesses of lenses, and its lower end is supported on one end of a lever *k*, to which a treadle (not shown) is connected, so that the operator can conveniently control the position of the 90 lens.

The upper ends of uprights *a'* are braced by cross-bars *a''*.

The operation is as follows: The roughly-formed lens is cemented to the support *h''* and 95 the latter fastened in the chuck, and then the spindle is set to revolving. The frame *e'* is moved back and forth, and the lens raised into contact with the grinding-disk. The horizontal guideways *g* control the traverse of the frame, while the disks *c'* keep the frame's pivot at one central point, which is in a line at right angles to the guideway *g*. The result is a paraboloidal surface on the lens, the 100

grinding-disk being always in a plane tangent to a parabola whose focus-line embraces the center of oscillation of said disk.

Grinding and polishing materials of different degrees of fineness are successively used until the lens is completely polished.

By turning the milled heads d^2 the blocks c can be set at any focus required, the verniers enabling the operator to read the distance 10 from the tangent slideway g to about one one-thousandth of an inch.

The swinging frame is here shown as provided with a bail m and a handle m' , by which to operate it.

15 It is evident that the invention is capable of embodiment in other forms than that here shown.

What I claim as new is as follows:

1. In an apparatus for grinding curved surfaces, the combination of an oscillatory holder having a sliding engagement with its pivot, and a guide-way engaging said holder and extending tangentially with respect to a circle described by the holder in oscillation about 25 its pivot.

2. In an apparatus for forming paraboloidal surfaces the combination of a suitably con-

structed supporting frame having vertical slide-ways, slides fitting the same and carrying pivots, adjustment screws supporting said 30 slides, a carrier or holder having sliding connection with said pivots, and horizontal guide-ways receiving projections on the carrier.

3. In an apparatus for forming paraboloidal surfaces the construction of a suitably constructed supporting frame having vertical slide-ways, slides fitted to the same, adjusting screws engaging the slides, disks pivoted to said slides, a frame having pendent arms extending at right angles to it and having a 40 sliding engagement with said pivoted disks, horizontal slide-ways on the supporting-frame and receiving projections on the pivoted frame, and a vertical spindle centrally located in the supporting-frame. 45

In testimony whereof I have signed my name to this specification, in the presence of two subscribing witnesses, this 28th day of June, A. D. 1894.

THEODORE M. CLARK.
